Benjamin S. Lewis - Mount Vernon, Ohio.

Letter Patent Dated November 19th 1833

The Schedule represents in true Letter Patent, and making part of the same, containing a description in the words of the said Benjamin S. Lewis, himself of his improvement in the art of cutting out or drafting gentlemen's garments.

To all to whom these presents shall come: Be it known that I Benjamin S. Lewis of Mount Vernon, in the County of ~~Marion~~ and State of Ohio, have invented a new and useful instrument, made use of in drafting gentleman's garments, - called the Delineator, and that the following is a full and exact description of the construction and mode of using said instrument as invented by me.

1st of its shape. The delineator is right angle triangle, the longest edge being 11 inches long, and the two short edges between 12 & 13 inches long, and is to be used in drafting in the place of a square.

2nd. Of the scale of divisions. The scale of divisions for the different sizes is contained on the three edges of the delineator as follows: They are calculated for 20 different sizes from twenty six inches whole circumference to forty nine of breast or waist measure, and are divided as follows; the whole circumference of a man's breast and waist is taken with an inch measure, and whatever number of inches he may measure round breast and waist, then the half of that number is taken and called the Breast and waist measure, and divided into one half,

fourth, eighth and twenty fourth, and again, into one third, sixth, twelfth and thirty second. They are contained on the delineator as follows: the divisions of halves, fourths, eights and twenty fourths for the different sizes are contained on the right hand end of the longest edge, the even numbers being on the lower edge and odd numbers being above them as designated

on draft, being divided by a larger line than those upon which the divisions are placed. The different divisions, that is to say, of halves, fourths &c are separated by large black lines.

The divisions of thirds, sixths, twelfths, and thirty seconds are contained on the two short edges of the delineator, the even numbers being on the right hand edge and the odd numbers on the left hand edge as designated on the draft, and the different divisions of thirds, sixths &c are divided, or distinguished by large black lines.

The numbers on the left hand end of the long edge commencing at 18 and ending at 1, are to govern the length of waist for different heights, for instance, if a man measure 52 inches in height then 13 inches which is opposite to 52 would be the proper length of waist for such height, or if the man be very round shouldered then it would require to be an inch or an inch and a half longer; on the contrary should he be quite straight or hollow backed then the variations must be reversed and the waist cut proportionately shorter. These numbers also answer for what is called height-measure, for instance where the diagrams require such a division of the height-measure, then the same number in the division of halves &c is to be used as is opposite the height of the customer, that is, if he be 52 inches high then 13 would be the number to be used for the height-measure and soon in such proportion for every other height.

5. Of the Protractor. The protractor is contained within the triangle above described. It is divided into sixty different angles or divisions. (on each side however, are omitted in consequence of their interfering with the scale of divisions on the longest edge or hypotenuse of the triangle) The centre of the protractor is designated by a notch and in the lower edge of the delineator, so that from the notch to the division marked 30 degrees forms a right angle with the longest edge of the instrument. The holes at the top and off the different angles of the protractor (see model) are to admit

of making marks on the cloth through them, so that any of the angles or divisions wanted may be obtained if necessary in drafting.

4th. of the degree. The degrees contained within the circle of the protractor and within a set of lines intended to represent the cloth for a coat, are made to assist young beginners in drafting. By placing them on the cloth the workman can have them always before him in a convenient form. They show the manner in which the coat is taken out of the cloth in order to produce a good, tasteful and well fitting garment.

5th. of the structure of the instrument. My intention at present is to have the three figures diagram A, engraved and printed on good paper, and fitted for use by having the paper glued or pasted upon a thin board or upon good firm paste board and the hole punched through at the angles of the protractor as represented in the model. I also contemplate having them constructed of brass copper and wood and the scale of divisions and diagrams given on both sides so as to render it still more substantial and convenient.

6th. of drafting back for just a new coat. commence at the bottom of your cloth go up from the bottom on line A, one third of the length of the customer which will give the proper length of skirt on line B, so in on line C, about one and three fourths inch for back lacing. Then go on line D as represented on draft. Then go up in line C, the one fourth of the height as directed in the waist calculations. Then apply the protractor at top of back and run to an angle of 32 degrees, then form line D as represented. Go out on line D, one twelfth of breast measure with one fourth of an inch added to it for lacing. Then come down on line C from line D one fourth of the height measure (being the same number in the division of four to one as opposite the customers height in the waist calculations) Then apply the protractor and run to an angle of 29 and 31, then form line E and F as represented. Go out on line D twice

7817X

and $\frac{1}{4}$ inch added to it for seam. Then form line A and B, lines as shown on draft. Go out on line C, from line C, one twelfth of waist - measured with one fourth of an inch added to it for seam. Then sweep curve D, by the length of waist or the distance from line B to line D. Go out on the bottom of back from line A, one third of waist measure and form line E as represented.

7th Of the front, directions for drafting. Commence by - squaring the back at the bottom opposite to where the back comes out. Then go up from bottom to the lower point of side seam or point F, one fourth of waist measure. Then apply the protractor and run to an angle of 38 degrees, then form line A, as shown on draft. Then go out on line A, from point F, one fifth of waist measure, with one fourth of an inch added for every - inch that the customer measures more round the breast than waist, or a fourth of an inch less he measures more round the waist than breast. Then square line B, from line A, then apply the back to get the proper distance from point F to line C, or upper point of side seam. Then square line C from line B. Then go up on line D, from line C, one eighth of the height meas ure. Then apply the protractor and run to an angle of 67 - degrees, then form line D, as shown on draft. Then come up from line B on line D, one fourth of ... - breast measure, for the back point of shoulder seam; then apply the back to get the front point of shoulder seam; then apply the protractor at the back point of shoulder seam on line D, and run to an angle of 14 degrees and form line E, as shown on draft. Then come - down on line E from line D, one half and one fourth of breast measure with one fourth of an inch added to it, which gives top of breast or top of curve C; and a twelfth more will give the top of line E. Then come out on line C, from line B, one fourth of breast measure to line E then come from line B, one eighth

78177

444

one fourth of an inch of width in front of eye as a worn hole through
back from front of eye on line O, on third of breast with one half
inch added, which gives the upper point of side seam. The curve
is swept by one fourth and one twenty fourth of breast measure.
The curve H is swept by one fourth of breast measure. The curve
I is swept by one fourth of breast measure. The curve is swept
by the distance from the upper point of side seam to the point
K. Then come up from point on lower point of side seam and
eighth of waist measure with one fourth of an inch added
to it, then form line K parallel with line A, as shown on
draft. Then come out on line K, one third of waist measure
and sweep curve L, with one third of waist measure. Then ap-
ply the back at point I and with one inch measure come out
on line K, the thickness of waist measure. Then form line
M as shown. Sweep curve O, by the length of waist so as to
form a regular junction with line M. Sweep curve P by one
fourth of breast measure.

7th of the Double back skirt - It is taken out of the cloth as represented
on draft directly above the fore parts in the following manner. Come
out from the edge of the cloth (line A) a sufficient distance for a
double or single pleat, as may be required, then measure up from
line B with the back to line C. Then apply the protractor and
turn to angles 24 and 30 degrees, then form lines C and D, as shown
on draft. Then come out on line D, one half of waist measure with
half an inch added to it, then come out on line B one third of a
waist measure with one half inch added to it, then form line E
as shown on draft, come out on line C from the pleat line the
distance from point E on fore parts to the lower end of line H, with
one and a half inch added for fullness under the flaps. Then cut
the back part of skirt measure and a fourth wide and form it as
shown on draft.

8th of the blouse - The should are taken out of the cloth alone

the back as shown on draft in front of lapelle in the following manner. Come down from top of cloth one twenty fourths of breast measured, then apply the protractor and run to an angle of 21 degrees and from line A. Go down on line A one half of breast measured and one twenty fourths added, then sweep the curve D with one fourth and one twenty fourths of breast measured. Then measured down with the inch measure from top of sleeve to elbow on line B, then to bottom on line C, which is one sixth and one thirty second of breast measured, from edge of cloth line C is got by an angle of 29 degrees. Go out on line D, one fourth and one thirty second of breast measured. Go out on line B, one third and one twenty fourths of breast measured. Then from lines B and C, as shown on draft. The under sides of the sleeves are cut by the upper sides and hooked in at top on out side down a edge, one twelfth of breast measured, and one thirty second at the inside down on edge at the top.

10th. Of the Brook Coat Skirt. The skirt of a Brook Coat is drawn in the following manner. Commence at the bottom of the cloth, apply the back and get the proper length on line A. Then go in from edge of cloth about an inch at top, and one half at bottom, which is for front facing, then get the size of the fore parts at the waist, leaving off the width of back, then sweep line C by that size from the top of skirt on line A. Then sweep line B, by the same size from where line C crosses line A, so as to form a junction with line C. Then square line D, from line A, so as to crop line B and C, where they come to a junction as shown on draft. Sweep line E by placing a tape or string in your fingers on line D, and with a piece of chalk at the other end on bottom of skirt, find the point on line D, when it will touch the bottom of skirt on A, and D, lined, then sweep as shown on draft.

10th. The collars, cuffs, flaps &c. are drafted by pattern to suit the various fashions. In the instrument of which the
